UNITED STATES PATENT OFFICE.

JOHN MARSTON GOODWIN, OF NEW YORK, N. Y.

DUMPING-SCOW.

SPECIFICATION forming part of Letters Patent No. 678,657, dated July 16, 1901.

Application filed January 21, 1901. Serial No. 44,092. (No model.)

To all whom it may concern:

Be it known that I, JOHN MARSTON GOODWIN, a citizen of the United States, and a resident of the city of New York, borough of 5 Manhattan, in the county and State of New York, have invented a new and Improved Dumping Scow or Vehicle, of which the following is a full, clear, and exact description.

This invention relates to improvements in 10 dumping scows, vessels, vehicles, bins, wagons, or the like; and the object is to provide a device of this character with a simple means for causing the discharge or unloading of the scow, vessel, or the like which will not careen, 15 and which has cargo-carrying compartments substantially V-shaped in cross-section.

I will describe a dumping-scow embodying my invention and then point out the novel features in the appended claims.

20 Reference is to be had to the accompanying drawings, forming part of this specification, in which similar characters of reference indicate corresponding parts in all the figures.

Figure 1 is an end elevation of a dumping- 25 scow embodying my invention. Fig. 2 is a top plan view. Fig. 3 is a cross-section of a vessel embodying my invention. Fig. 4 is a partial side elevation thereof. Fig. 5 is a side view of a detent employed. Fig. 6 is a 30 cross-section of a portion of the vessel, showing methods of supporting the discharging and replacing devices. Fig. 7 is a side view of a device for supporting one side of the side valves and swinging the same when dis- 35 charging. Fig. 8 is a top plan view of detents, a detent-shaft, counterweights, and showing methods of attaching same to the bulkheads. Fig. 9 shows side elevations and top views of a replacing-hook employed, and 40 Fig. 10 shows top and side views of a replacing-link employed.

The dumping-scow comprises a body portion 1, divided by vertical partitions 2 into a series of independent compartments, the 45 bottoms of all these compartments being inclined downward, and each bottom comprises one or more center valves 3 and downwardly- swinging side valves 4. The upper edges of the side valves are connected to the vertical 50 side pieces 5 of the body by means of bar- hinges 6, and, as shown in the drawings, Fig. 7, two bar-hinges 6 are arranged together,

or, in other words, the hinges are arranged in pairs, mounted to swing on a longitudinally-extended bar or hoisting-shaft 7. The 55 two hinge-sections are connected at the lower end by a pivot-pin 8, which passes through a keeper 9, attached to the outer side of the valve 4.

As here shown, the body is supported on 60 two scows or vessels 10, there being a space between these vessels through which the cargo may be discharged, as will be hereinafter described. It is to be understood, however, that while I have shown the body as mounted 65 on scows it may be mounted on stationary supports or on wheels.

The center valves 3 are connected to V- shaped struts 11, which at their lower ends or apexes are provided with rollers 12. These 70 struts are mounted to swing on a rod 13, extended longitudinally through the body and at the lower portion thereof, and extended lengthwise of the body underneath the rod 13 and laterally thereof are center-valve- 75 releasing shafts 14. Connected to these shafts 14 are detents 15. These detents have curved bearing-surfaces, the sides of which are provided with flanges to prevent lateral movement thereof in relation to the rollers 12, 80 which are extended to bear upon the curved surfaces of these detents. The several detents on a shaft or rod 14 are of varying widths—that is, the detents for the second compartment will have a bearing-surface 85 twice that of the detents for the first compartment, and the detents carrying the center valve of the third compartment will have a bearing-surface three times that of the first compartment, and so on throughout all the 90 compartments there may be in the body. This is to provide for unloading the several compartments one after the other—that is, by rotating the shafts 14 all the detents will be moved; but all of them except the first 95 will remain in engagement with their rollers 12, while the first ones become disengaged from their rollers, allowing the center valves and side valves to fall. It will be noted that the inner or free edges of the side valves 100 when in closed position rest upon the outer edges of the center valves. After discharging the first compartment the shafts are to be still further turned to release the valves

of the second compartment, and so on until all the compartments are discharged. I will state here that while the above description might indicate that the valves of both sides 5 are operated together, it is to be understood that the valves of one side only may be opened, while the others remain closed, depending upon the side of the vessel from which the load is to be discharged, or, as will herein- 10 after appear, the load may be discharged between the two scows or vessels 10.

Arranged at opposite sides of the body portion are short chutes 16, and to these short chutes auxiliary chutes 17 are hinged so that 15 they may be swung upward against the body when not in use. When in use, however, these swinging chutes 17 will be lowered, as indicated at the right-hand side of Fig. 3, so that the load will discharge over the same. 20 In the upper portion of each fixed chute is mounted to swing a retarding valve or plate 17^a. This retarding-plate has its end walls pivoted to the sides of the chute 16, and its front plate may be lowered more or less into 25 the discharging material.

Arranged to close the space between the lower edge of a valve 3 when said valve is in its open position and the upper end of the fixed chute 16 is an auxiliary valve 18. This 30 auxiliary valve 18 is made in the form of a plate and is mounted on spring-yielding hinges 19, which swing on rods 20. These hinges not only permit the swinging of the said valves 18, but, being yielding, form buffer-abutments for engaging with the valves 4 when they are swung to their open position, as indicated at the left-hand side of Fig. 6. When the said auxiliary valves 18 are open, as shown at the left-hand side of Fig. 6, the 40 material discharged will be directed between the vessels or scows 10, the said open valves 18 forming stops and directing-valves. The valves 18 are moved by hand-power to their open or closed position.

45 A hoisting arrangement for the purpose of replacing the center valves and side valves to carrying position consists of a hoisting-shaft 7, mounted on the side of the vessel, one movable pulley-block 22, a chain 23, connected at 50 one end to the upper portion of a partition and extending around said pulley 22 and thence around a fixed pulley 24 and to the shaft 7, which may be turned by any suitable means. Connecting with the two divergent 55 members of the chain 23 are hoisting-hooks 25, adapted to be by hand placed in engagement with links 26, connected to the valves. The novel formation of the hoisting-hooks 25 allows them to disengage themselves from the 60 links 26 by gravity when the strain of hoisting is released—that is, each hoisting-hook has a weighted extension 27, which will rock the curved surfaces 28 of the hooks on the upper side of the valves when the hoisting strain 65 is released, and when this strain is released the hooks will move downward until they come into engagement with the valves. Then

the weighted ends will cause said hooks to swing outward out of engagement with the links 26, as it will be noted that the chain 23 70 is on an incline when the hooks are in their holding position. When the hooks are by hand placed in connection with the links and the chains drawn taut, the weighted ends of the hooks will be drawn upward, causing the 75 forked members of the hooks to engage the inner and outer surfaces of the eyes, so as to hold tightly when lifting the valves. The links 26 are mounted to slide in openings in the valves, so that when said valves are swung 80 to their open position the said links at their inner ends will be practically flush with the inner surfaces of the valves. By the use of the movable pulley 22 the hoisting-power becomes double that usually obtained by the use 85 of the fixed pulleys. Therefore it is feasible to raise both the center valves and the side valves at the same time. The branches of the chain 23 must be of such length and attached at such points to the main chain that 90 the side valves precede the center valves just before reaching the carrying position, as indicated by the dotted lines in Fig. 6. In other words, this is to prevent the closing of the 95 side valves before the passing of the ends thereof over the ends of the center valves while said center valves are moving to closed position.

Attached to one end of the shafts 14 are arms 29, provided at their free ends with slots, 100 through which a pin projecting from the vertically-operating bar 30 extends. This bar 30 is provided with a piston adapted to operate in a cylinder 31 and by means of which rocking motion may be imparted to the shafts 14. 105 The chutes 17 may be raised and lowered by means of chains 32, and it will be noted that the outer sides of the struts 11 are provided with teeth 33, with which a crowbar or other device may be engaged to start the valves 110 should they become frozen or otherwise temporarily locked.

Having thus described my invention, I claim as new and desire to secure by Letters Patent—

1. A dumping scow or vehicle, comprising a body portion divided into a series of compartments, side valves and center valves forming downwardly and inwardly inclined floors for the compartments, means for supporting the valves in their closed position, and means operating to release the valves of the several compartments successively, substantially as specified.

2. In a dumping scow or vehicle, a body 125 mounted thereon and divided into compartments, swinging side valves and swinging center valves forming bottoms for the compartments, the inner edges of the side valves resting on the center valves when in closed 130 position, struts connected to the center valves, a rod on which said struts are mounted to swing, rollers carried by said struts, detent-operating bars or rods extended through the

body, and segmental detent-plates on said rods or bars with which the rollers are designed to engage, the detents underneath the several compartments varying in width, substantially as specified.

3. A dumping scow or vehicle, comprising a body portion, divided into compartments, side valves hinged at their upper edges to the side pieces of the body, center valves mounted to swing on a rod extended lengthwise of the body, means for holding the valves in their closed position, means for releasing the valves, and means for moving the valves to closed position, comprising chains adapted to become automatically disengaged from the valves when lifting-pressure is relieved, substantially as specified.
4. A dumping scow or vehicle, comprising a body portion, side valves mounted to swing on said body portion, center valves mounted to swing in said body portion, a hoisting-chain for the valves, and lifting-hooks connected to projections of said chains and adapted respectively to engage with links on the side and center valves, the said sections of the chain being of different lengths so that the side valves will be completely closed before the center valves are completely closed, substantially as specified.
5. In a dumping scow or vehicle, a body portion, swinging valves forming the bottom thereof, fixed chutes extended laterally from the body, and extension-chutes mounted to swing on the fixed chutes, substantially as specified.
6. In a dumping scow or vehicle, a body portion, swinging side valves on said body

portion, swinging center valves, fixed chutes extended laterally from the sides of the body, and auxiliary valves adapted to direct material into said fixed chutes or to direct material to discharge below the body portion, substantially as specified.

7. In a dumping scow or vehicle, a body portion, side valves mounted to swing on said body portion, center valves mounted to swing on said body portion, the said valves forming the bottom of the body when closed, chutes extended laterally from the body, auxiliary valves for directing material over the chutes or for directing material to discharge below body portion, and spring-yielding hinges supporting said auxiliary valves, the said hinges forming buffers for the side valves when swung open, substantially as specified.

8. In a dumping scow or vehicle, a body portion, valves forming the bottom of said body portion, chutes extended laterally from the body portion, and retarding devices in said chutes, substantially as specified.

9. In a dumping device, a body portion, center valves forming portions of the bottom thereof, triangular struts to which said valves are connected, the said struts having teeth at the outer ends, and lifting devices for engaging with the struts, substantially as specified.

In testimony whereof I have signed my name to this specification in the presence of two subscribing witnesses.

JOHN MARSTON GOODWIN.
